UNITED STATES PATENT OFFICE.

JOHN STITSEL, OF DELAWARE TOWNSHIP, DEFIANCE COUNTY, OHIO.

WIND-ENGINE.

SPECIFICATION forming part of Letters Patent No. 259,236, dated June 6, 1882.

Application filed March 13, 1882. (No model.)

To all whom it may concern:

Be it known that I, JOHN STITSEL, a citizen of the United States of America, residing at Delaware township, in the county of Defiance and State of Ohio, have invented certain new and useful Improvements in Wind-Engines, of which the following is a specification.

My invention relates to a wind-engine for driving mills and other purposes; and the objects of my improvement are, first, to provide a wind-engine with one paddle in a horizontal position while the other will be perpendicular; second, to furnish a starting wheel and lever; third, to provide keys and stops so arranged that the paddles or wings may be let loose or locked in an easy position; and, fourth, to secure a wind-engine which will utilize the force of the wind and combine cheapness, durability, strength, and power. I attain said objects by the construction, arrangement, and combination of the several parts, as illustrated in the accompanying drawings, in which—

Figure 1 is a side elevation of my invention. Fig. 2 is a plan view, and Fig. 3 a detail view.

Similar letters of reference indicate similar parts throughout the several views.

A is a wooden frame-work or support, consisting of the bottom frame, a' a', uprights a, and the top E.

a' is provided in its center with a journal or bearing, b, for the reception of the lower end of the perpendicular shaft S, which turns or revolves therein.

S is a perpendicular revolving shaft, passing from a' up through the center of E, D, and H, its top end being made fast in the wheel-hub H and revolving therewith, and is provided with a shank having a bearing against a projection on E, but being free in E and D.

H is what I call my "wheel-hub." It is made fast to the top of shaft S, revolving therewith, and is composed of two cross-pieces, or of one piece having four arms, the ends of these arms being provided with small uprights x x, through which pass the wing or paddle shafts.

C C are two wing or paddle shafts, carrying four paddles, one at each end of each shaft. The ends of the shafts C C pass through holes in the uprights x x, so as to be loose therein and yet held in position. C C are cut out in

the center, where they cross each other in the manner as shown in Fig. 2, which form wing-stops, and designated by the letters y y; or the shafts may be straight, one being set higher than the other, with wing-stops attached to the shaft at other points. On the ends of C, at the side and beyond x, is the projection d', which, with d, forms a lock to hold the wings in position. In the drawings two are shown, one on one of the ends of each of the shafts C.

d is a lock-key hung or hinged on the end of H, and of shape as shown in Fig. 3, and is for the purpose of locking and unlocking the wings. Two are shown; but there may be four, and there may be four of d' to correspond with the number of d.

D is a wheel between H and E. It is loose on the shaft S, and it has on its rim projections o' o', which rest in the support-hooks o o on the end of hub H on the under side, O O being wires bent to form loops, their ends being secured to H. In these loops o' o' slide or have free play. o' o' are sufficiently long to strike against the lock d. D, at its edge underneath, is provided with beveled teeth or cogs n, in which e' plays.

B are wings or paddles firmly secured on the ends of shafts C C, so that the paddle on one end of the shaft is perpendicular, while the one on the other end of the shaft is horizontal, each paddle being perpendicular to its opposite horizontal or horizontal to its opposite perpendicular.

e' is a wire spring, secured at one end to the side of E and at the other to one end of lever e.

e is a wooden lever, being a narrow strip of wood, one end secured to the end of e' and at the other to the rope or chain c, and provided on top with the projection e'', which engages with the ratchet or cog's end. e is otherwise disconnected, so that it has free play. e is passed up over or through a projection or arm on side of E, so that it will move freely, and by pulling will elevate the end of e, as shown in Fig. 1.

All the parts are constructed of wood except as indicated; or they may be made of any suitable material.

The manner of operation is as follows: When the wind strikes, it throws one paddle endwise to it, or horizontal, while the other is

perpendicular, thereby catching mostly all the wind by the perpendicular one, the horizontal one offering no resistance to the wind by this arrangement. The entire force of the wind is utilized for the purpose of propelling the wheel. When the wheel is in motion, upon pulling on the cord *c* the lever *e* will be elevated and the keys *d* are let loose, and the wings or paddles are locked in an easy position to stand still. In starting, simply pull up the lever *e* and give a quick jerk, and then let the lever drop.

The wings or paddles heretofore described may be ballasted heavy or light to suit the use to which they may be applied.

Having described my invention, what I claim as new, and desire to secure by Letters Patent, is—

1. A wind-engine in which one paddle is horizontal while the opposite paddle is perpendicular, substantially as shown and described.

2. A combination, in a wind-engine, of a lever and keys, whereby the wings are locked and unlocked, substantially as described and set forth.

3. In a wind-engine, the combination of the spring *c'*, lever *e*, provided with projection *e²*, and the ropes *c*, substantially as shown and described.

4. In a wind-engine, the wing-shafts *C C*, provided with stops *y y*, or equivalent, and having at their ends the paddles *B B*, one paddle at one end being perpendicular and the other paddle at the other end being horizontal, in combination with the wheel-hub *H*, provided with projections or bearings *x x*, substantially as described, and for the purpose set forth.

5. In a wind-engine, the wheel-hub *H*, provided with projections *x x* and loops *o o*, in combination with wheel *D*, provided with ratchet *n*, projection *o'*, the shaft *S*, and key *d*, substantially as shown and described.

6. In a wind-engine, the combination of the

key *d*, projection *d'*, projection *o'*, loop *o*, and wheel-hub *H*, substantially as described and shown.

7. In a wind-engine, the combination of the lever *e*, provided with projection *e²*, and cords *c*, with the wheel *D*, provided with ratchets *n* and projection *o'*, whereby a starting and stopping is secured, substantially as shown and described.

8. In a wind-engine, the combination of the key *d* and projection *d'*, substantially as described and shown.

9. In a wind-engine, the wheel *D*, provided with ratchet *n* and projection *o'*, substantially as shown and described.

10. In a wind-engine, the spring *c'*, secured at one end to frame *E* and at other end to lever *e*, substantially as described and shown.

11. In a wind-engine, the lever *e*, provided with projection *e²*, substantially as shown and described.

12. In a wind-engine, the shafts *C C*, having paddles *B B*, the paddle *B* at one end of each shaft being secured horizontally to a paddle perpendicular on the end of the same shaft, substantially as described and shown.

13. In a wind-engine, the combination of the revolving shaft *S* with wheel-hub *H*, wheel *D*, top frame, *E*, and bottom frame, *a'*, provided with bearing *b*, substantially as shown and described.

14. In a wind-engine, the combination of the frame *A*, composed of uprights *a a*, bottom frame, *a'*, provided with journal *b*, and top frame, *E*, with revolving shaft *S* and spring *c'*, substantially as described and shown.

In testimony whereof I affix my signature in presence of two witnesses.

JOHN STITSEL.
